UNITED STATES PATENT OFFICE.

GEORGE W. COMEE, OF WASECA, MINNESOTA.

COFFIN-FASTENER.

1,044,498.

Specification of Letters Patent.

Patented Nov. 19, 1912.

Application filed June 21, 1912. Serial No. 705,080.

To all whom it may concern:

Be it known that I, GEORGE W. COMEE, a citizen of the United States, residing at Waseca, in the county of Waseca and State of Minnesota, have invented certain new and useful Improvements in Coffin-Fasteners; and I do hereby declare the following to be a full, clear, and exact description of the invention, such as will enable others skilled in the art to which it appertains to make and use the same.

My invention relates to improvements in fastening devices, especially adapted for use in securing the lids or covers of coffins or caskets to the bodies thereof and, to this end, it consists of the novel devices and combinations of devices hereinafter described and defined in the claims.

The invention is illustrated in the accompanying drawings wherein like characters indicate like parts throughout the several views.

Referring to the drawings, Figure 1 is a plan view of the body of the coffin with the cover removed therefrom; Fig. 2 is a side elevation of the coffin with some parts of the cover broken away and with some of the exposed parts shown in vertical section; Fig. 3 is a bottom plan view of the cover removed from the body of the coffin, with some parts of the fastening devices shown in section, taken on the line $x^2 x^3$ of Fig. 2; Fig. 4 is a longitudinal vertical section taken through the cover and body of the coffin at one of the side fastening devices; and Fig. 5 is a plan view of the latch shown in a different position from that shown in Fig. 3.

The numeral 1 indicates, as an entirety, the body of the coffin which, as shown, is of substantially the same form as that disclosed and claimed in U. S. Patent, Number 265,022, entitled "Burial case corners," and issued to me of date September 26th, 1882. 45 Detachably secured to the body 1, by an endwise sliding movement, is a flat cover 2, but, as far as my invention is concerned, said cover may be of the well known box form or of any other desired form.

50 The cover 2 is detachably secured to the body 1, by means of a plurality of headed studs 3 and coöperating wedge blocks 4. As shown in Fig. 1, there are four of these headed studs 3 and they are arranged in 55 pairs, one pair on each side of the body 1.

At their lower ends, the headed studs 3 are anchored to the body 1 with their heads projecting slightly above the upper edge thereof. The wedge blocks 4 are countersunk in the under face of the cover 2, a distance to permit their outer faces to lie flush therewith. The wedge blocks 4, corresponding in number with the headed studs 3, are secured to the cover 2 by means of screws 5. Outwardly flaring notches 6 are formed 60 one in each wedge block 4, and the notches 6 of each pair of wedge blocks 4 are alined and adapted to receive, by endwise sliding movement of the cover 2 the body portions of the studs 3. Underlying each notch 6 65 and extending forward therefrom, is an entrance channel 7, adapted to receive the heads of the studs 3. The inner faces of the prongs of the wedge blocks 4 are formed 70 with wedge acting surfaces 8 that extend 75 obliquely to the inner face of the cover 2. These wedge acting surfaces are arranged to engage the under surfaces of the heads of the studs 3, and, under the closing endwise sliding movement of the cover 2, draw 80 said cover, by a wedging action, onto the upper edge of the body 1.

For securing the cover 2 against endwise movement, after the same has been clamped onto the body 1 by means of the coöperating 85 headed studs 3 and notched wedge blocks 4, I provide the cover 2 with a latch 9 that automatically locks with a headed stud 10 secured to the intermediate upper edge portion of one of the ends of the body 1. The 90 stud 10, as shown, is identical in form with the headed studs 3 and its head lies in the same plane therewith. Secured to the under side of the cover 2, by wood screws 11, is a latch plate 12 having an outwardly flaring notch 13 adapted to receive the body portion of the stud 10 by an endwise sliding movement of the cover 2; and, at the same time, the headed studs 3 are engaged 95 by the wedge block 4. The latch plate 12 is set into the inner face of the cover 2 and lies flush therewith. Formed in the cover 2, directly under the notch 13, and extending in advance thereof, is a channel 14 of substantially the same size as the channel 7, 100 adapted to receive the head of the stud 10.

The latch 9 comprises a lever 15 secured at its intermediate portion, for swinging movement, to the under side of the latch plate 12, by means of a pivot pin 16. One 110

end of the lever 15 terminates in a hook 17 and its other, or outer end, terminates in a laterally projecting finger piece 18 that extends outside of the latch plate 12 into a position to be operated from the outside of the body 1. The hook 17 is arranged for swinging movement across the notch 13 for interlocking engagement with the body portion of the stud 10 at a point directly under its head.

For automatically moving the hook 17 into interlocking engagement with the headed stud 10, a cam arm 19 is integrally formed on the lever 15, which cam arm 19 projects in the same plane with the lever 15 but diverges therefrom. This cam arm 19 is arranged to be engaged by the body portion of the stud 10, under the endwise sliding closing movement of the cover 2 and cammed thereby laterally, a distance sufficient to swing the latch 9 on its pivot pin 16 and thereby carrying the lock hook 17 across the notch 13 and into interlocking engagement with the body portion of the stud 10.

Normally, the lock hook 17 engages one of the walls of a recess 2^a formed in the cover 2, under the latch plate 12, and holds the cam arm 19 in its proper position to be engaged by the headed stud 10. To prevent too free a movement of the latch 9, the latch plate 12 is formed with a bulge portion 20 over which the lock hook 17 frictionally slides.

The above described fastening devices, while extremely simple and of small cost to manufacture, are thought to be highly efficient for the purpose had in view.

What I claim is:—

1. The combination with a coffin body and a removable cover therefor, of headed studs and a lock pin secured to said body, notched wedge blocks secured to said cover, arranged to embrace said headed studs for drawing said cover onto said body during an endwise sliding movement thereof, a swinging lock hook pivoted on said cover, means operated by engagement with said lock pin, during the closing sliding movement of said cover, to move said lock hook into interlocking engagement with said lock stud, and means extending to a point outside of the coffin for releasing said lock hook, substantially as described.

2. The combination with a coffin body and a removable cover therefor, of headed studs and a lock pin secured to said body, notched wedge blocks secured to said cover, arranged to embrace said headed studs for drawing said cover onto said body during an endwise sliding movement thereof, a swinging lock hook pivoted on said cover, a cam arm on said lock hook arranged to engage said lock pin during the closing sliding movement of said cover to move said lock hook into interlocking engagement with said lock stud, and a finger piece on said lock hook extending to a point outside of the coffin for releasing said lock hook, substantially as described.

In testimony whereof I affix my signature in presence of two witnesses.

GEORGE W. COMEE.
